UNITED STATES PATENT OFFICE.

ALFRED H. THOMPSON, OF VENICE, CALIFORNIA.

HOT-WATER-PRESSURE COMBINED DOMESTIC AND HEATING SYSTEM.

1,240,101.

Specification of Letters Patent. Patented Sept. 11, 1917.

Application filed October 21, 1912, Serial No. 727,073. Renewed October 25, 1913. Serial No. 797,358.

To all whom it may concern:

Be it known that I, ALFRED H. THOMPSON, a citizen of the United States, residing at Venice, in the county of Los Angeles and State of California, have invented a new and useful Hot-Water-Pressure Combined Domestic and Heating System, of which the following is a specification.

This invention relates to a novel apparatus whereby the hot water in a water system for domestic supply may be practically applied for heating radiators placed at or below the level of the heater which supplies the heat to said hot water system.

An object of the invention is to make provision whereby the heating system can all be placed on one floor as in one-story cottages, and bungalows and one-floor apartments and flats, and yet allow the radiators to be installed at any level desired. It is usually considered desirable to place the radiators on or close to the floor and such a location of the radiator brings the bottom thereof to or below the level of the heater by which heat is applied to such one-story system.

It is found, however, that in hot water heating systems heretofore known the heat from the heater will not descend to a level lower than the heater and this condition prevents the required heat from reaching the radiator thus located.

So far as I am aware hot water heating systems employing a heater and a radiator with water connections between the heater and the radiator have been constructed upon the theory that the heat is conducted from the heater to the radiator by a circulation of the water in the system; but I have discovered that if provision is made whereby the water circuit can be maintained in the heating system the heated water will rapidly pass through the system to not only the level at which the heat is applied, but also to a certain point below such level; and that the lowest point below such level to which the heated water can thus be driven is determined by natural physical forces; and that it is possible to construct a hot water heating and domestic supply system in which the radiator is placed at or below the level of the heater, and it is possible to so construct the system that there will be an unbroken water circuit leading upward from the heater to a predetermined point, and thence downward and to the radiator and thence through and from the radiator to the lower

end of the heater and thence through the heater to complete the circuit, and at the same time the hot water of the system may be drawn from for domestic use without breaking the circuit. 60

A feature of this invention resides in the provision of means whereby I insure the maintenance of such unbroken circuit, and this I effect by providing at the highest 65 point of the circuit a distributor forming a part of such circuit and having a sufficient capacity to keep the circuit from being broken by accumulations of air or steam that may occur under the forces operating 70 in the system during the practical use thereof.

That is to say said distributor is constructed of a considerable size sufficient to accommodate the air and steam accumulations that may occur in practical operation; and to hold the same out of the radiator circuit so that such circuit will not be broken thereby and the domestic hot water service pipe leading to the faucet is connected to the 80 distributor above the level of the hot water circuit. 75

It is practical to supply the hot water heating system through a supply pipe from the water mains of a pressure supply system 85 and to depend upon the yielding pressure of said supply system to regulate the pressure within the hot water system and the expansion of steam from the heat of the heater may result in forcing water from the heating system out toward the main, thus forming a steam space at the top of the system. 90

There is always a certain amount of occluded air contained in the water supply flowing to such systems from the main and 95 such air will gradually accumulate at the highest point of the system, and when the accumulation of air or the accumulation of steam as above set forth is sufficient to break the hot water circuit, the conduction of heat 100 through the hot water system is arrested. A feature of this invention, therefore, consists in applying a hot water distributor to the heating circuit between the top thereof and the connection of the domestic service 105 pipe, so that in case there is any steam or air in the hot water circuit, it will rise out of said circuit and be stored without breaking such circuit, and will be drawn off through a cock of the domestic water pipe 110 when said cock is open.

I have discovered, however, that it is nec-

essary to preserve certain relations with regard to the levels of the distributor, the heater and the bottom of the radiator circuit, and that it is necessary that the connection of the hot water circuit with the distributor shall be at least twice as high above the heater as the heater is above the bottom of the radiator circuit, and that the reason for this is the necessity of gaining sufficient weight of liquid in the heating system between the heater and the distributor to force the heat down below the heater to the bottom of the radiator circuit.

The accompanying drawings illustrate the invention.

Figure 1 is an elevation showing partly in section portions of a structure in which is installed in accordance with this invention a hot water pressure combined domestic and heating system sectioned in part.

Fig. 2 is an enlarged detail from line x^2 , Fig. 1 to show the thermostat.

The heater 1 communicates through the riser 2 with a closed, upright, single-chambered combined storage reservoir and distributor 3 of which the height is greater than the width and from which the drop pipe 4 leads to the horizontal floor pipe 4' and through the valve 5, radiator 6, horizontal return pipe 8 to the rising heater pipe 9 which communicates through the branch 10 with the heater 1. The distributor is of greater diameter and capacity than the pipes communicating with it.

The heater pipe 9 communicates through an upward extension 9' including the valve 11 with the bottom of the service tank 12 which is connected at its top by pipe 13 with the drop pipe 4.

The pressure service pipe 14 enters the heater pipe in its extension or branch 9' between the valve 11 and the branch 10; and when the cocks 19 are open, water from the supply pipe 14 may enter the system to supply service pressure thereto.

The burner 15 is arranged below the coiled heater pipe 1 in the usual manner to heat the contents of such pipe and when the valves 5 and 11 are opened, the burner in operation and the service cocks 19 closed, water will circulate through the pipe 10, heater 1, riser 2, distributor 3, drop pipe 4, tank pipe 13 and the upper extension or branch 9' of the pipe 9 to pipe 10, and so on. Gas is supplied to the burner 15 by the pipe 16 controlled by a thermostatic valve 17 of well-known construction.

A domestic service pipe 18, separated from the other pipes in the system, leads from the distributor 3 above the level of the riser 2 and is connected with the domestic service cocks 19. A gas valve 20 is provided to cut off the gas supply, not shown.

The distributor is preferably of limited dimensions, so that the water therein may

be quickly heated when the heater is in operation, the water rising from the heater through the riser 2 to the distributor and displacing colder water in the distributor and in the descending pipe 4. It is thus seen that the water in the distributor becomes heated almost directly from the heater. If the valve 11 is open, the cold water displaced from the distributor will be short-circuited through the domestic tank 12, the extension 9', the heater pipe branch 10 and the heater 1, eventually filling the domestic tank with hot water which is first passed through the distributor tank 3.

The thermostatic valve 17 may be set so that when the water which passes through the heater branch 10 reaches a certain temperature, the gas supplied through pipe 16 will be shut off, leaving only a small flame as a pilot light, not shown, at the burner 15, to maintain the fire; so that when the temperature of the water becomes lower the gas may again be turned on to maintain the requisite temperature.

While the valve 11 is thus open, hot water may be drawn from the faucets or domestic service cocks 19 and will flow directly from the distributor which will be supplied with hot water from the domestic tank 12 under the pressure from service pipe 14 until the hot water has been drawn whereupon the circulation upward through pipe 2 will continue and will supply hot water to the distributor, so that whenever there is any hot water in the system it can be drawn off at the domestic cocks.

When the valve 11 and the service cocks 19 are opened the system is supplied with cold water flowing from service pipe 14 into the bottom of the domestic tank and hot water will be drawn from the top of the domestic tank and from the distributor until the domestic tank has been filled with cold water from the main.

When the service cocks 19 and the valve 11 are closed and the burner 15 is lighted, the hot water from the heater 1 displaces the cold water, if any, in the distributor and a circulation is established downward through the drop pipe 4, then horizontally through the floor pipe 4', radiator 6, return pipe 8, heater pipes 9 and 10, heater 1 and riser 2.

I have discovered that it is important that the distributor 3 be elevated above the heater level at 1 of the system by a distance equal to or greater than twice the distance from the heater burner 1 level at 15, Fig. 1, to the lowest water level at 4' because of the difference between the density of the mass of water and air extending from the distributor 3 at the highest water level of the circuits to the heater level at 15 and the density of the mass of water extending from said heater level to the lowest water level 130

of the circuits so as to obtain maximum circulation. For instance, if the distance from the heater level at 15 to the lowest water level at 4' is assumed to be four feet, 5 then the distance from said heater level at 15 to the distributor 3 should not be less than eight feet but is preferably made as much greater than eight feet as is convenient in order to afford maximum speed 10 of water circulation through the heater.

It is also advisable to extend the distributor tank 3 above the level of the pipe 2 so that the circulation of water is not broken in case steam is generated in the system. The 15 said steam may gather in the upper portion of the distributor and by connecting the service pipe 18 to the upper part of the distributor the latter may be relieved of said accumulated steam through the faucets or 20 service cocks 19. By this provision the water also is delivered from the highest point of the distributor which is the hottest part of the system.

Should both valve 11 and the radiator 25 valve 5 be left closed and the heater started inadvertently, the circulation through the same will be blocked and the coils of same damaged by overheating. To avoid this a circulation pipe 21, connecting pipe 4 with 30 pipe 9 and extending below pipe 4' is supplied, will afford a path that is always open for free circulation through the heating coils, as the passage through said circulation pipe is uninterrupted by valves or other 35 obstructions.

Viewing the domestic heating system broadly it is seen to comprise a water circuit including a distributor 3, pipes 4 and 13, a domestic tank 12, pipe 9', valve 11, a portion 40 of pipe 9, pipe 10, heater 1 and pipe 2; the distributor being situated substantially above the level of the domestic tank and the domestic tank being situated substantially above the level of the heater. A portion of 45 pipe 4 below pipe 13 obviously communicates with the water circuit above the domestic tank and in connection with pipe 4' and valve 5 leads the hot water to radiator 6 which extends below the level of the bottom 50 of the heater; while the pipe 8 leading from said radiator communicates through a part of pipe 9 to the lower portion of the aforesaid water circuit. Also the faucets or 55 cocks 19 are connected with a pipe 18 leading the hot water from the distributor or upper portion of said water circuit.

When either or both of the faucets or cocks 19 are opened and the valve 11 is closed, hot water may be drawn off continuously from the distributor 3 through the domestic service pipe 18 and the active parts 60 of the system would operate just as though the domestic tank 12 were not present. Also when the faucets 19 and the valve 11 are 65 closed and the valve 5 is opened, hot water

may be continuously conveyed through the radiator 6 and the circuit completed just as though the domestic tank 12 were not present. Furthermore, when faucets 19 and valves 11 and 5 are closed, the emergency 70 circuit will be completed by way of the pipe 21 effecting a continuous communication from pipe 4 to pipe 9 without regard to tank 12. In these instances, the tank is not required; the distributor constituting a sufficient reservoir for the reserve hot water. 75

The heater 1 has an inlet from the pipe 10 as indicated by the arrow below the character 10 and an outlet at a higher level into the pipe 2 as indicated by the arrow below 80 the character 2. The conduit formed by the pipe 2 affords direct communication from the outlet of the heater to the distributor 3. A conduit is provided by the pipes 4 and 4' affording direct communication from the 85 distributor to the radiator and a conduit is afforded by the pipes 8, 9 and 10 connecting the radiator 6 to the inlet of the heater. A by-pass circuit affording direct communication from the distributor to the inlet at the 90 bottom of the heater is formed by a portion of pipe 4 together with pipe 13, domestic tank 12 and the pipes 9', 10. A supply pipe 14 leads into the pipe 9' and discharges water under pressure through pipe 9' and the 95 pipe 10 into the heater. Said supply pipe serves to supply water under pressure to the system. The hot water service cock 19 may be located at any level usual therefor, but the conduit formed by the pipe 18 which 100 is connected to the cock 19 must be connected to the distributor above the level of the inlet to said distributor in order that any accumulation of air or steam may be drawn off from the combined reservoir and distributor with the hot water at the service 105 cock.

I claim:—

1. In a domestic heating system, the combination of a hot water circuit including a 110 distributor, a domestic tank, and a heater, the distributor being situated substantially above the level of the domestic tank, and the domestic tank being situated substantially above the heater; a radiator, a pipe communicating with the hot water circuit near the upper part of the domestic tank, said pipe leading to said radiator, a pipe leading from said radiator and communicating with the lower portion of said water circuit. 115

2. In a domestic heating system, the combination of a hot water circuit including a distributor, a domestic tank, and a heater, the distributor being situated substantially above the domestic tank, and the domestic 125 tank being situated substantially above the level of the heater; a radiator, a pipe communicating with the hot water circuit near the upper part of the domestic tank, said pipe leading to said radiator, a pipe lead- 130

ing from said radiator and communicating with the lower portion of said water circuit, service cocks, and a pipe leading from the upper portion of said water circuit to said 5 service cocks.

3. In a domestic heating system, the combination of a water circuit including a distributer, a domestic tank, and a heater, the distributer being situated substantially above 10 the level of the domestic tank, and the domestic tank being situated substantially above the level of the heater, a radiator, a pipe communicating with the water circuit above the tank and leading to said radiator, a pipe 15 communicating with the lower portion of said water circuit and also leading to said radiator, a valve in one of said pipes leading to said radiator, a valve in the water circuit, service cocks, a pipe communicating 20 with the upper portion of said water circuit and leading to said service cocks, and a supply pipe for the system.

4. In a domestic heating system, the combination of a water circuit including a distributer, a domestic tank and a heater, the distributer being situated substantially above 25 the level of the domestic tank and the domestic tank being situated substantially above the level of the heater; a radiator, a pipe 30 communicating with the water circuit above the tank and leading to said radiator, a pipe leading from said radiator and communicating with the lower portion of said water circuit, service cocks, a pipe communicating 35 with the upper portion of said water circuit and leading to said service cocks, and a supply pipe for the heating system.

5. In a domestic heating system, the combination of a water circuit including a distributer, a domestic tank, a heater, and a 40 valve, the distributer being situated substantially above the level of the domestic tank, and the domestic tank being situated substantially above the level of the heater, a 45 radiator, a pipe communicating with the water circuit above the level of the tank and leading to said radiator, a pipe communicat-

ing with the lower portion of said water circuit and also leading to said radiator, a valve in one of said pipes leading to said radiator, service cocks, a pipe communicating 50 with the upper portion of said water circuit and leading to said service cocks, a circulatory pipe having one end connected to one of said pipes leading to said radiator, and the other end of said circulatory pipe being connected with the other of said pipes leading to said radiator, said circulatory pipe extending below the level of the lowest 55 point of either of said pipes leading to said 60 radiator.

6. In a hot water pressure combined heating and domestic service system, the combination of a distributer, a domestic tank, a heater and a radiator; the distributer being situated substantially above the level of the domestic tank, the domestic tank being situated substantially above the level of the heater, and a radiator extending below the level of the bottom of the heater; a pipe connection from the top of the heater to the side of the distributer near the bottom thereof; a second pipe leading from the bottom of the distributer to the radiator; a return pipe leading from said radiator to the bottom of the heater; the bottom of the tank being also connected with said return pipe; and the tank at its top being connected with said second pipe leading from the bottom of the distributer; domestic service cocks; a 70 domestic service pipe leading from the top of the distributer to said cocks; and a circulation pipe having an unobstructed passage therethrough, said circulation pipe connecting the second pipe with the return pipe out- 75 side of said radiator and descending below the level of said second pipe.

In testimony whereof, I have hereunto set my hand at Los Angeles, California, this 11th day of October, 1912.

ALFRED H. THOMPSON.
